United States Patent Office

Des. 208,988
Patented Oct. 24, 1967

208,988

GARDEN HOE

Howard A. Anderson, Pittsburgh, Pa., and Henry J. Rosendall, Grand Rapids, Mich., assignors to Bissell Inc., Grand Rapids, Mich., a corporation of Michigan

Filed Aug. 24, 1966, Ser. No. 3,568

Term of patent 14 years

(Cl. D35—2)

FIG. 1.

FIG. 2.

FIG. 3.

FIG. 2 is a top plan view thereof; and

FIG. 3 is an end view thereof, taken on line 3—3 of FIGURE 1.

We claim:

The ornamental design for a garden hoe, substantially as shown and described.
